(57) **CLAIM**

The ornamental design for an emergency lighting container,
as shown.

DESCRIPTION

FIG. 1 is a front perspective view of an emergency lighting container showing my new design.

FIG. 2 is a front view thereof.

FIG. 3 is a rear view thereof.

FIG. 4 is a left side view thereof. The right side view is a
mirror image of the left side view; and,

FIG. 5 is a top view thereof. The bottom view is identical to
the top view.
